United States Patent Office

Des. 186,224

Patented Sept. 29, 1959

186,224

PUSHBUTTON OPERATOR UNIT

Charles G. Sims, Fox Point, Wis., assignor to Cutler-Hammer, Inc., Milwaukee, Wis., a corporation of Delaware

Application March 30, 1959, Serial No. 55,241

Term of patent 14 years

(Cl. D26—13)

Figure 1 is an isometric view of a pushbutton operator unit incorporating my new design;

Fig. 2 is a side elevational view thereof;

Fig. 3 is an end elevational view thereof.

The dominant features of the design are shown in solid lines.

I claim:

The ornamental design for a pushbutton operator unit, substantially as shown and described.
